[57] CLAIM

The ornamental design for a photograph album, substantially as shown and described.

DESCRIPTION

FIG. 1 is a front elevational view of a photograph album showing my new design, the rear elevational view being substantially similar except that the central recess and plate have been omitted.

FIG. 2 is a bottom plan view thereof, the top plan view thereof being the same; and

FIG. 3 is a cross-sectional view taken along the plane 3—3 in FIG. 1.

FIG. 1.

FIG. 2.

FIG. 3.
